UNITED STATES PATENT OFFICE.

HENRY H. WESTINGHOUSE, OF NEW YORK, N. Y., ASSIGNOR TO THE WESTINGHOUSE AIR BRAKE COMPANY, OF PITTSBURGH, PENNSYLVANIA, A CORPORATION OF PENNSYLVANIA.

COMBINED CAR AND PIPE COUPLING.

1,106,431.

Specification of Letters Patent. Patented Aug. 11, 1914.

Application filed November 17, 1911. Serial No. 660,805.

To all whom it may concern:

Be it known that I, HENRY H. WESTINGHOUSE, a citizen of the United States, residing at New York, in the county of New York and State of New York, have invented new and useful Improvements in Combined Car and Pipe Couplers, of which the following is a specification.

This invention relates to automatic car couplers, and more particularly to that type having means for coupling the train brake pipe or other fluid pressure conduits. A combined coupler of the above type is shown in prior Patent No. 708,747 of George Westinghouse, dated September 9, 1902, and broadly stated, this coupler comprises a coupler head pivotally connected to the car frame and adapted to automatically engage with a counterpart coupler head, a lock for retaining the coupler head in engagement with its counterpart head, and one or more fluid pressure conduits in the head having packed port openings adapted to make fluid tight joints with corresponding conduit port openings in the counterpart coupler head. Where couplers of the above character or other couplers having locking devices are employed in service, it may sometimes happen that the locking device will fail, either wholly or partially, to effect the desired locking engagement with the counterpart head, so that, without the knowledge of the attendant, the train may be started with some coupler not properly locked to its counterpart coupler. As a consequence, the coupler in question is liable to separate from its counterpart coupler and thereby cause a break-in-two of the train.

The principal object of my invention is to provide means for warning or indicating to the attendant when a coupler is not properly locked.

In prior patent of George Westinghouse No. 887,296, dated May 12, 1908, means are provided for holding the coupler lock in locking position and as a preferable construction I have shown my improvement in a form utilizing this holding means, although it will be understood that the invention is not so limited, but contemplates the use of various other embodiments within the scope of the invention.

In the accompanying drawing, Figure 1 is a horizontal section of a coupler head with my improvement applied thereto; Fig. 2 a

section on the line *a—a* of Fig. 1; and Fig. 3 a vertical section of the end portion of a coupler head, showing in elevation the face which engages a corresponding face of a counterpart coupler head.

As shown in the drawing, the coupler head may comprise a casting 1 having a projecting portion 2 and a recess 3 into which the projecting portion 2 of a counterpart coupler head enters.

Centrally arranged, longitudinally of the coupler is a vertical plane surface having one or more openings, such as opening 20 communicating with a fluid pressure conduit 4 and provided with the usual gasket 5 for making a tight joint with a similar gasket of a counterpart coupler head. Above and below this plane surface are formed transverse projections 6 adapted to engage and interlock with similar projections on a counterpart coupler head. Each head is provided with a pivoted latch or locking lever 7 having a cam surface for engaging a surface on the projecting portion 2 of the counterpart coupler head. A projecting arm 8 of the locking lever 7 is pivotally connected to an operating rod 9 and a spring 10 acts on the rod 9 in a direction tending to force the lever 7 into locking position.

A roll 11 is carried by the rod 9 in position to be acted upon by a double cam 12 and said cam 12 is adapted to be rotated manually by means of a handle (not shown) secured to shaft 13, so that when said handle is shifted to either of its extreme positions, the roll 11 is moved outwardly and the locking lever is thereby shifted to its unlocked position.

The inner portion of the locking lever 7 is provided with an inclined surface and for holding the locking lever in locking position, a small piston 14 is provided having a tapered stem 15 adapted to engage said inclined surface. A port 16 leads from the fluid pressure conduit 4 to the chamber 17 at one side of the piston 14, so that fluid is supplied to said piston when the coupler members are coupled together and fluid under pressure is supplied to the conduit 4.

When two coupler heads are brought together by impact, the projecting portion 2 of each head enters the recess 3 of the other head, depressing the latch or locking levers 7 until the transverse projections 6 pass one another, whereupon the springs 10 force the

locking levers 7 with their cam surfaces out into engagement with the surfaces on the projecting portion 2, thereby pressing the coupler heads tightly together with the gas-
ket openings in register. The usual angle
5 cocks are then turned to open communication through the conduit 4, whereupon fluid under pressure flows through passage 16 to chamber 17, thus forcing the piston 14 out-
wardly, so that the tapered stem 15 engages
10 the inclined surface on the lever 7.

According to my improvement, an atmospheric exhaust port 18, communicating with that side of piston 14 which is opposite to the chamber 17, is provided and a port 19 around piston 14 is adapted to establish communication from chamber 17 to the opposite side of the piston. Piston 14 is also provided with a seat 21 adapted in the extreme 20 outward or locking position of the piston to seat and cut off communication from port 19 to port 18. It will now be evident that when the piston 14 is not seated, fluid is free to flow from chamber 17 through port 19 to the 25 atmospheric exhaust port 18 and consequently, whenever the locking lever 7 fails to move to its fully locked position, the tapered stem 15 being prevented from moving outwardly to its full extent, the piston 14 can not seat and fluid then escapes to the 30 atmosphere and serves to warn the attendant that the coupler is not properly locked.

It is not essential that the locking device shown be employed to carry out my invention, as it will be evident that other devices 35 may be designed for this purpose within the scope of my invention, in which the position of the locking lever operates to control the means for warning the attendant that the 40 coupler members are not properly coupled.

Having now described my invention, what I claim as new and desire to secure by Letters Patent, is:—

1. An automatic car coupler comprising a 45 coupler head provided with a projecting portion adapted to engage a similar portion on a counterpart coupler head and an opening in said projecting portion for coupling a

fluid pressure conduit, a locking lever for clamping the coupler heads together, and means operated according to the position of the locking lever for venting fluid from said conduit. 50

2. An automatic car coupler comprising a coupler head provided with a projecting portion adapted to engage a similar portion on a counterpart coupler head and an opening in said projecting portion for coupling a fluid pressure conduit, a locking lever for clamping the coupler heads together, and means operated by said locking lever in positions other than the fully locked position for venting fluid from said conduit. 55

3. An automatic car coupler comprising a coupler head provided with a projecting portion adapted to engage a similar portion on a counterpart coupler head and an opening in said projecting portion for coupling a fluid pressure conduit, a locking lever for clamping the coupler heads together, fluid pressure operated means for holding said lever in locking position, and a port controlled by said fluid pressure operated means for venting air from said conduit upon failure of said fluid pressure controlled means to 70 fully move to its locking position. 75

4. An automatic car coupler comprising a coupler head provided with a projecting portion adapted to engage a similar portion on a counterpart coupler head and an opening in said projecting portion for coupling a fluid pressure conduit, a locking lever for clamping the coupler heads together, a piston subject to the fluid pressure of said conduit and having a stem for engaging said locking lever, a port for permitting the escape of fluid under pressure past said piston, and a seat on said piston for closing communication through said port in the fully 80 locked position of said piston. 85

In testimony whereof I have hereunto set my hand.

HENRY H. WESTINGHOUSE.
